UNITED STATES PATENT OFFICE.

WINSLOW ALDERDICE, OF AKRON, OHIO, ASSIGNOR TO THE AKRON IRON COMPANY, OF SAME PLACE.

DIE.

SPECIFICATION forming part of Letters Patent No. 329,801, dated November 3, 1885.

Application filed January 26, 1885. Serial No. 153 974. (No model.)

To all whom it may concern:

Be it known that I, WINSLOW ALDERDICE, a citizen of the United States, residing at Akron, in the county of Summit and State of Ohio, have invented a new and useful Improvement in Dies for Drawing, Compressing, and Polishing Cold Metal Bars, of which the following is a specification.

The principal features of my invention consist of the die being formed with an opening through it, in part a tapering curve and in part tangential to such curve, and also the rear end being of a flaring form.

In the drawings forming a part of this specification, Figure 1 is a section of the die and its holder. Fig. 2 is a side view of the die, and Fig. 3 is a front view of the same.

The die *a o* is formed with an opening, *c*, through which cold metal bars may be drawn and thereby compressed and polished. The front part of opening *c* is flaring in substantially a parabolic curve, and the rear part of the opening is cylindrical and tangential to the curved part, except at the end, which is slightly flaring. In this form of opening *c* there is space for lubricating material in the front part around the bar to be drawn, and the gradually-decreasing contraction of the opening inward to the cylindrical part facilitates the operation of drawing, compressing, and polishing the bar, as the contraction is least where the force of compression is greatest. The flaring front part of opening *c* may be formed, if desired, in a different curve from a parabola, as an arc of a circle to which the cylindrical part of the die is tangential. At the rear end of the die its opening *c* is flaring, to prevent breaking the die from the expansion of the metal bar when released from compression in drawing it through the die. Such expansion is slight, but of great force, and if the die at the rear end of its opening *c* is cylindrical the edges or corner are liable to be broken by the expansion of the bar on emerging from the opening *c*.

The die consists of the inner steel part, *a*, and an outer wrought-iron part or jacket, *o*. The diameter of steel part *a* is reduced at

its rear end, forming a shoulder, *s*, and the wrought-iron jacket *o* has a reduced rear part, 50 *o'*, forming a shoulder, *s'*, for a bearing against die-holder *b*. The jacket *o* is sweated on the steel part—that is, it is heated at or about a red heat, then placed on the die and allowed to shrink there by cooling. The jacket forms 55 a permanent part of the die, which is made to fit closely in its holder *b* by driving it in the latter, which is formed to receive it.

Instead of the two parts *a o*, the die may be formed of a single piece of steel. 60

I claim as my invention—

1. A die for drawing, compressing, and polishing cold metal bars, having an opening the front part of which is of a curved tapering form, and another part is formed with parallel sides tangential to the curved part, substantially as described. 65

2. A die for drawing, compressing, and polishing cold metal bars, of such form that the intersection of a plane through the axis 70 of the die-opening with the side of the opening will be in part a parabolic curve and in part parallel with the axis of the opening and tangential to said curve, substantially as described. 75

3. A die for drawing, compressing, and polishing cold metal bars, formed with an opening that is flaring at both ends, and has parallel sides intermediate the flaring parts, substantially as described. 80

4. A die for drawing, compressing, and polishing cold metal bars, formed with an opening, *c*, having a flaring rear end, *n*, substantially as described.

5. The die *a o*, formed of the steel part *a* and a wrought-iron jacket, *o*, shrunk thereon, substantially as described. 85

6. The die *a o*, having a reduced rear end, forming a shoulder-bearing, *s'*, against the die-holder *b*, in combination with said holder, 90 formed to receive the die, substantially as described.

WINSLOW ALDERDICE.
